UNITED STATES PATENT OFFICE.

GEORGE LISPENARD, OF NEW YORK, AND EDWARD C. TRUYTER, OF WEST NEW BRIGHTON, NEW YORK, ASSIGNORS TO NORDLINGER, CHARLTON FIRE WORKS COMPANY, OF NEW YORK, N. Y., A CORPORATION OF NEW JERSEY.

MACHINE FOR MAKING FUSES.

SPECIFICATION forming part of Letters Patent No. 757,580, dated April 19, 1904.
Application filed February 11, 1902. Serial No. 93,509. (No model.)

To all whom it may concern:

Be it known that we, GEORGE LISPENARD, residing at the city of New York, borough of Brooklyn, county of Kings, (and whose post-office address is 585 Bainbridge street, in said borough of Brooklyn,) and EDWARD C. TRUYTER, residing at West New Brighton, county of Richmond, State of New York, (and whose post-office address is Houghwont avenue, in said West New Brighton,) both citizens of the United States, have invented certain new and useful Improvements in Machines for Making Fuses, of which the following is a specification.

The object of our invention is to provide a machine for the economic manufacture of fuses for explosives.

It consists of a mechanism for making the inflammable material into a cylindrical shape, means for forming the fuse into a compact body, and a mechanism for feeding the element forming the fuse through the binding device and reeling the fuse out of the machine.

Our invention is illustrated in the accompanying drawings, in which the same reference-letters indicate similar parts in all the figures.

Figure 1 illustrates a side view of the machine. Fig. 2 illustrates the top view. Fig. 3 illustrates a vertical section of the feeding device, taken on the line 3 3 of Fig. 4. Fig.

4 illustrates a rear view of the feeding device. Fig. 5 illustrates the folding means for the wrapper of the fuse. Fig. 6 is a rear view of the folding means. Fig. 7 illustrates a perspective view of the feeding-trough, and Fig. 8 illustrates a cross-section of the fuse.

In Fig. 1, A indicates the base of the machine to which are fastened the bracket a' and the framework a'' , which consists, preferably, of a rib extending from the bracket a' transversely across the base A to approximately the center thereof and from there longitudinally of the base nearly to the end thereof, and provided at proper points with suitable supports as may be needed for the various parts of the mechanism. The bracket a' supports a hopper B for the fuse material, which may

be gunpowder or other pulverulent matter. The hopper is supported on a neck b , in which is a vertical conical-shaped opening b' , through which pass the inflammable material b'' and the central cord b''' of the fuse. This central cord b''' gives a body for the fuse in its process of manufacture and affords a means of readily handling the fuse without breaking it. The cord b''' is fed off from a reel. (Not shown in the drawings.)

Below the hopper is supported the horizontal feeding-trough C, having a ring c' for guiding the cord b''' into the feeding-trough C. This ring c' is supported in a groove c'' . At the other end of the feeding-trough is located the head c''' , by which the feeding-trough is supported in the bracket a' . The trough has a channel c''' and at one end a segmental annular opening c'''' .

From the reel D a ribbon d' , of paper or other material, is guided over tension-roller d'' and into the feeding-trough C through the opening c'''' . The shape of the opening c'''' gives the ribbon d' the shape of the channel c''''' . The inflammable material b'' falling from the hopper is caught by the ribbon and, together with the cord b''' , is drawn through the folding device E.

The folding device E is fastened to the lower end of the hopper, and comprises an arm which is curved downwardly and outwardly, so that its lower portion is parallel to the axis of the feeding-trough and extends in the direction that the fuse moves through said trough. This lower portion is provided with a cylindrical opening e' , through which the inflammable material is fed, and a slot e'' . This portion is also provided with a yoke e''' , against which the feeding-trough is pressed in order to position the feeding-trough properly relative to the hopper. The ribbon in passing through the cylindrical opening e' is folded about the inflammable material b'' and the cord b''' . From the folding end of the folder E the elements of the fuse pass through the conical opening c'''' , which further brings

the fuse into a compact body. From the feeding-trough C the fuse passes to a binding-machine.

The binding-machine (illustrated in Fig. 2) is driven by a pulley F, mounted on a transverse shaft a^4 , the outer end of which is supported in the bearing f^4 of the support a^3 . On the shaft a^4 is also mounted a bevel-gear f , adapted to mesh with and operate two similar bevel-gears f^2 and f^3 , which are mounted on the ends of a longitudinally-arranged shaft supported in a bearing f^4 , carried upon a suitable support rising from the rib a^2 . The bearing f^4 is provided at its side toward the bevel-gear f with a lug f^x , in which the inner end of the transverse shaft a^4 is journaled. To each of the gears f^2 f^3 are attached frames f^5 , which carry spools f^6 on spindles f^7 , passing through the center of the spools and journaled at their lower ends in suitable bearings f^{11} on the frames f^5 . Springs f^8 are pivotally supported on the headed lugs f^9 on the frames f^5 , their free ends pressing against the spindles f^7 , thus holding them in place against their bearings f^{11} , except when removed to release the spools f^6 or when the spools are replaced. The removal of the springs f^8 from contact with the spindles f^7 is easily accomplished by revolving said springs half a turn on the lugs f^9 . An additional function of the springs f^8 is to prevent any undue movement of the spindles while the machine is in operation. Also attached to the frames f^5 f^6 are arms f^9 f^{10} , which form guides for the fuse and also for the thread which is fed from the spools f^6 f^7 through the holes f^{10} in the guiding-arms. The fuse is drawn through the first guide-arm f^9 , and at the same time the gear f^2 revolves the spools about the fuse in one direction, thereby winding the fuse. As the fuse passes through the bearing f^4 and the guide-arm f^9 of the frame fastened to the gear f^3 the thread fed from the spools of that frame winds the fuse in the opposite direction, thereby binding the fuse into a compact body. The fuse is then reeled by a reeling mechanism.

The reeling mechanism consists of a gear G, fastened to the gear f^2 , which is turned by the gear f . A gear g' meshes with the gear G. The gear g' is fastened to a shaft g^3 , gear G, which is supported in bearings g^2 g^3 , rising from the base A, and the rib a^2 . At one end of the shaft g^3 are located the endless screws g^4 g^5 , which mesh with the worm-wheels g^6 g^7 , mounted upon transverse shafts g^8 g^9 , which are carried by bearings g^{10} g^{11} , suitably supported from the rib a^2 . On the shafts g^8 g^9 are also mounted wheels g^{12} g^{13} , provided with grooves g^{14} on their surfaces. The fuse d^2 is wound around the wheels g^{12} g^{13} in their grooves g^{14} , and then it is passed down to the reel. By the means just described the fuse d^2 is

given the proper tension and its movement⁵ through the machine is given a uniform rate.

For operating the reel a grooved wheel H is attached to the shaft g^8 . A belt h' plays somewhat loosely over the wheel H and the grooved wheel h^2 , which is fastened to the reel. The belt h' is thus permitted to slip as the fuse-reel becomes filled with the windings of the fuse.

The mechanism above described for making a compact fuse may be varied without departing from the spirit of our invention.

What we claim as new, and desire to secure by Letters Patent, is—

1. In a fuse-machine, the combination with a hopper for the fuse material, means for feeding a strip of paper below the same, and means for feeding a cord immediately above said paper strip, of a trough extending transversely on either side of the discharge-opening of said hopper and having a segmental and annular opening at one end adapted to guide said paper strip, a separate guide on said trough for said cord, and means for folding said paper strip around said cord and fuse material.

2. In a fuse-machine, the combination with a hopper for the fuse material and means for feeding a strip of paper transversely below the same, of a trough, extending transversely on either side of the discharge-opening of said hopper and having a segmental and annular opening at one end and adapted to receive and guide said paper strip through said trough in a curved form, means for folding said paper strip with its contents into a compact mass, and means for binding a continuous thread about said mass.

3. In a fuse-machine, the combination with a hopper for the fuse material, means for feeding a strip of paper below the same and means for feeding a cord immediately above said paper strip, of a trough, extending transversely on either side of the discharge-opening of said hopper and having a segmental and annular opening at one end, adapted to guide said paper strip, a separate guide on said trough for said cord, means for folding said paper strip around said cord and fuse material, means for further compressing said fuse into a more compact mass, and means for binding a continuous thread about said mass.

4. In a fuse-machine, the combination with a hopper for the fuse material, of a feeding-trough adjacent said hopper, means for feeding a strip of paper through said feeding-trough, and a folding device located in said trough but separated therefrom and having a cylindrical opening for taking up said paper and contents and compressing the same into a compact mass.

5. In a fuse-machine, the combination with a hopper for the fuse material, of a feeding-trough adjacent said hopper, means for feeding a strip of paper through said feeding-

trough, and a folding device located above said trough comprising a curved arm extending downwardly from said hopper, and having an annular opening for taking up said paper and contents and compressing the same into a compact mass.

6. In a fuse-machine, the combination with a hopper, of a trough located below the same and having a segmental and annular opening cut in at one end thereof, means for feeding a strip of paper, through said opening, below said hopper, and means for folding said paper and contents, comprising a curved arm extending downwardly from said hopper and having a cylindrical opening for taking up said paper and contents and compressing the same into a compact mass.

7. In a fuse-machine, the combination with a hopper for the fuse material, of a feeding-trough adjacent said hopper, means for feeding a strip of paper through said feeding-trough, a folding device located above said trough comprising a curved arm extending downwardly from said hopper and having an annular opening for folding said paper and contents, and further means for compressing said paper and contents into a compact mass, comprising a head on said trough having a central conical bore therethrough.

8. In a fuse-machine, the combination with a hopper, of a trough below said hopper having a segmental and annular opening cut in at one end thereof, means for feeding a strip of paper through said opening below said hopper, means for folding said paper and contents comprising a curved arm extending downwardly from said hopper and having a cylindrical opening therethrough, and further means for compressing said paper strip and contents into a compact mass, comprising a head on said trough having a central conical bore therethrough.

9. In a fuse-machine, the combination with a hopper for the fuse material, of a feeding-trough adjacent said hopper, means for feeding a strip of paper through said feeding-trough, means for feeding a cord through said trough immediately above said paper strip, and a folding device located in said trough but separate therefrom, and having a cylindrical opening for folding said paper strip around said cord and fuse material.

10. In a fuse-machine, the combination of a hopper having a conical neck and adapted to receive the fuse material and a central cord for the fuse, a reel for the covering of the said fuse, a tension-roll for the said covering, guides for the said covering and the said central cord, a compressing device having a cylindrical opening and a slot, and means for further compressing the fuse into a compact body.

11. In a fuse-machine, the combination with a hopper for the fuse material, of a semicylindrical feeding-trough arranged transversely below said hopper, means for feeding a strip

of paper through said feeding-trough, means located in said trough for forming the fuse into a cylindrical shape, a cylindrical head on said trough, having a central conical bore for further compressing the fuse material, and mechanism for winding continuous threads, in opposite directions, about said compressed material.

12. In a fuse-machine, the combination with a hopper for the fuse material, of a semicylindrical feeding-trough arranged transversely below said hopper, means for feeding a strip of paper through said trough, means located in said trough for forming the fuse into a cylindrical shape, comprising a curved arm extending downwardly from said hopper and having a substantially cylindrical opening in the lower part thereof, a head on said trough having a conical bore for further compressing the fuse material, and mechanism for winding continuous threads, in opposite directions, around said compressed mass.

13. In a fuse-machine, the combination with a hopper for the fuse material, of a semicylindrical feeding-trough arranged transversely below said hopper, means for feeding a strip of paper through said feed-trough, means located in said trough for forming the fuse into a cylindrical shape, a cylindrical head on said trough having a central conical bore for further compressing the fuse material, mechanism for winding continuous threads, in opposite directions, about said compressed material, grooved wheels for drawing the said fuse through said winding mechanism, and means for operating said grooved wheels.

14. As an article of manufacture, a folding device for fuse-making machines and the like, comprising a curved arm with a yoke secured thereto, having a cylindrical opening and slot passing through said arm adjacent to said yoke.

15. In a fuse-machine, a trough, means on said trough for folding a paper ribbon, and means intermediate of the ends of the trough for raising the said paper clear of the trough, and folding it about a pulverulent material.

16. In a fuse-machine, a trough, means at one end of said trough for folding a paper ribbon, means intermediate of the ends of the trough for raising the said paper clear of the trough, and folding it about a pulverulent material, and means at the other end of said trough for further folding said paper about the said material.

17. In a fuse-machine, a trough, a folder centrally located intermediate of the ends of the trough, and a yoke on said folder to properly hold the same with relation to the trough.

18. In a fuse-machine, a hopper, a neck supporting said hopper and provided with a passage, a curved arm extending from a point adjacent to said passage, and a cylindrical opening in said arm extending in a direction substantially perpendicular to that of the passage.

4
19. In a fuse-machine, a trough which supports a paper ribbon at its extremities, means located intermediate of said extremities and above the trough for folding the paper ribbon about the pulverulent material, and raising said paper clear of the central portion of the trough.

Signed at the city of New York, county of

New York, and State of New York, this 7th day of February, 1902.

GEORGE LISPENARD.
EDWARD C. TRUYTER.
